MINIATURE BUILDING STRUCTURE

Filed Jan. 24, 1934

FIG 4

UNITED STATES PATENT OFFICE

2,028,229

MINIATURE BUILDING STRUCTURE

Hans P. Luhn, New York, N. Y.

Application January 24, 1934, Serial No. 708,027

9 Claims. (Cl. 46—26)

This invention relates generally to building structures, and more particularly to devices for constructing miniature reproductions of building structures.

5 The demand for devices adapted for the construction of buildings in miniature is quite well recognized in the field of toys. This demand has, however, expanded into the field of architecture, since it is extremely difficult for persons unfamiliar with architectural drawings to visualize therefrom the appearance of a building as a whole or the relative proportions, shapes, and arrangement of its parts. When a building is reproduced in miniature, however, a mental picture 10 of the full sized object is possible.

Heretofore, miniature reproductions have generally been constructed on individual order principally from parts made specially for the particular job, and hence have been quite costly. Moreover, such miniature reproductions have usually been confined to a simulation of the exterior of the contemplated building structure, because of the difficulty, time and expense which would be involved in attempting to reproduce the more intricate nature of the interior.

According to this invention, the foregoing difficulties are overcome by using parts of various standard sizes for walls, floors, ceilings, roofs, windows, staircases, fireplaces, chimneys, etc., 30 and by providing a novel connector or key for simply, conveniently, efficiently and quickly securing these parts together at desired points.

My invention relates primarily to the construction, arrangement, and combination of parts which, together with other features, will become more apparent to persons skilled in the art as the specification proceeds and upon reference to the accompanying drawing, in which:

40 Fig. 1 is a perspective view of a plurality of wall parts joined in various ways to illustrate the facility with which different structures may be formed;

Fig. 2 is a top plan view of Figure 1;

45 Fig. 3 is a perspective view of one form of connector or key.

Fig. 4 is a perspective view of another form of connector or key;

50 Fig. 5 is an elevation illustrating the application of another form of the connector or key in joining ceiling or similar members with parts simulating exposed beams;

Fig. 6 is a bottom plan view of the assembly of Figure 5; and

55 Fig. 7 is a section on line 7—7 of Figure 6. Referring now more particularly to Figs. 1, 2,

and 3, at 10 is shown an assembly of wall members 11, marked, for convenience of identification, as 11a to 11f, inclusive, for the purpose of illustration. The members 11, which may advantageously be made of wood, are shown as of uniform height and thickness but of various widths. By proper selection of interfitting parts of various widths a wall may be reproduced substantially to scale, say, for instance, a scale of 1 inch to 1 foot.

5 Each member 11 is shown provided at opposite ends with a centrally arranged longitudinal groove 12 and a plurality of spaced transverse grooves 13, thus forming a plurality of groove intersections. The transverse grooves 13 are preferably equally spaced.

10 The width of each member 11 may be a function of its thickness. A convenient system to follow is to make the width of any member 11 a multiple of a standard thickness. It is also convenient to have the number of transverse grooves 20 equal to this multiple. Following these principles, which are suggested for the purposes of illustration, a member with one transverse groove would have a square cross section, the grooves 12 and 13 forming an equilateral cruciform locking 25 depression, as indicated at 16, so that any face of the member may be joined, in the manner hereinafter described, in abutting relation with another member 11. As illustrated, the member 11a has two transverse grooves, the member 11b 30 three, the member 11c four, the member 11d three, the member 11e six and the member 11f three. A member with two transverse grooves would have a width equal to twice its thickness, etc., and any member would have a number of 35 contiguous cruciform locking depressions at each end which correspond to the multiple of its thickness, so that another member 11 may be joined 40 in abutting relation with either the front or rear face of such member in any of a number of positions, corresponding to the number of locking depressions, as well as in abutting relation with either end face thereof. The thickness of any member may be worked into the structural scheme not only to represent wall thickness but 45 also as a unit in the face of the wall, for instance, to represent an off-set in a wall as illustrated at 14 or to represent length in a wall as illustrated at 15.

50 The grooves 12 and 13 are preferably of uniform width and the distance between the longitudinal groove 12 of any member 11 and either side face 24 thereof is preferably made equal to the distance between either end face 25 and the nearest transverse groove 13.

The longitudinal and transverse groove arrangement on the opposite ends of the members 11 makes it possible to joint the members 11 together readily and conveniently by means of a simple connector, for instance, a key or locking member of the type shown at 17 in Figure 3.

Member 17 is preferably of solid soft rubber and in shape comprises a shank 18 and two cross or end bars 19 arranged at opposite ends of the shank 18 to form an I shape construction. Locking member 17 may be made of any other resilient material, and is proportioned so that an end bar 19 may be pressed into any transverse groove 13 and the contiguous portion of the shank 18 into the intersecting longitudinal groove 12 or an end bar 19 may be pressed into a longitudinal groove 12 and the contiguous portion of the shank 18 into any intersecting transverse groove 13. The end bars 19 and shank 18 are preferably slightly larger than the grooves so that when pressed into the grooves they will hold themselves in place. The length of the shank 18 is preferably slightly less than twice the distance between any longitudinal groove 12 and either side face 24, or, which is the same thing, slightly less than twice the distance between either end face 25 and the nearest transverse groove 13.

As seen in Figures 1 and 2 the members 11a and 11b are secured together with their end faces 25 abutting. The particular member 17 visible at the top has one end bar 19 in a transverse groove 13 of the member 11a and its other end bar 19 in a transverse groove 13 of the member 11b with the shank 18 fitting into those portions of the longitudinal grooves 12 of the members 11a and 11b which fall therebetween.

As previously pointed out, the shank 18 is slightly shorter in length than the associated portions of grooves 12, and the stretch necessary 40 to force it home places sufficient tension thereon to hold the parts firmly together. Members 11a and 11b are, of course, secured together in a similar manner at the bottom.

The manner of securing one end face 25 of a member 11 to a side face 24 of another member 11 to form a corner, is illustrated at 20 and 21. At 20 an end face 25 of the member 11b is secured to a side face 24 of the member 11c by pressing one cross bar 19 into the nearest transverse groove 13 of the member 11b and pressing the other cross bar 19 which projects from the end face of member 11b into the longitudinal groove 12 of the member 11c. In this case, the longitudinal groove 12 of the member 11b is in alignment with the adjacent transverse groove 13 of the member 11c so that the shank 18 fits into the end of the longitudinal groove 12 of the member 11b and into one end of the adjacent transverse groove of the member 11c.

60 The same arrangement is illustrated at 21 where an end face 25 of the member 11d abuts the rear side face 24 of the member 11e to form a corner.

A manner of securing two members together to 65 form an off-set in a wall is illustrated at 22 where the cross bars 19 fit into the longitudinal grooves 12 of the members 11c and 11d and the shank 18 which extends normally of the faces 24 fits into the intermediate aligned portions of the adjacent 70 transverse grooves 13.

A manner of securing an end face 25 of a member 11 to a side face 24 of another member 11 to 75 form a partition is illustrated at 23 where one cross bar 19 of the locking member fits into the longitudinal groove 12 of the member 11e and

the other cross bar 19 fits into the nearest transverse groove 13 of the member 11f. The shank 18 fits into the intermediate aligned portions of the adjacent transverse groove 13 of the member 11e and of the longitudinal groove 12 of the member 11f.

It will, of course, be obvious that the member 11f may be shifted to other positions along the side face 24 of the member 11e so as to bring the shank 18 into any of the transverse grooves 13 of the member 11e. In fact the same is also true at 20, 21, and 22, should this be desired.

When it is desired to take an assembled structure apart, the adjoining structural members 11 may readily be disconnected and separated by grasping them and sliding them in opposite directions on each other.

Referring now to Figures 5-7, it will be noted that the longitudinal grooves 26 and transverse grooves 27 of each member 28 are formed in a 20 face of the member 28, are parallel to its edges and are equally spaced from said edges. The locking members 17a are shown with shanks 18a which are somewhat longer than the shanks 18 although this would not be essential if the 25 grooves 26 and 27 were arranged closer to the edges of the member 28. This would be as convenient if the special structure to be hereinafter described for securing the members 28 to the beam 29 were not desired.

When the beam structure is desired, the beam 29 is formed with opposed longitudinal grooves 30 and opposed longitudinal tongues 31. The members 28 are provided with peripheral grooves 32 and peripheral tongues 33. The tongues 31 35 on the beam 29 fit into the grooves 32 of the members 28 and the tongues 33 on the members 28 fit into the grooves 30 on the beam 29 as shown in Fig. 5. The locking members 17a secure the parts together as illustrated. Beam 29 is provided with slots 34 to permit passage there-through of the shanks 18a of the locking members 17a. As shown, the shanks 18a fit into the transverse grooves 27 and the cross bars 19a fit into the longitudinal grooves 26. Inasmuch as 45 the locking members 17a are elastic, and the shanks 18a are of a length slightly less than twice the distance between any groove and the adjacent parallel side edge of the member 28 the parts are held together with sufficient tension to 50 hold them in place. In securing the beam 29 and the members 28 together, it is usually more convenient first to fit the locking members 17a into the appropriate grooves 26 and 27 of the members 28 and then interfit the tongue and 55 groove portion of the beam with the corresponding portions of the associated members 28. In order to do this it will, of course, be necessary to pull the members 28 away from one another 60 against the tension of the locking members 17a, but the elasticity of these members makes this possible.

Inasmuch as the grooves 32 and tongues 33 on the members 28 are peripheral the portions 36 and 37 of the grooves and tongues, respectively 65 at the ends of members 28, permit the use of a cross beam should such a structure be desired, or should it be desired to arrange the beam between two ends of the members 28 instead of between two sides thereof. It will be noted that 70 the body portions 38 of the members 28 overlap the tongues thereon so that the edges 39 of the members 28 abut each other to form a smooth and continuous surface over the beam 29.

While the use of soft rubber for the locking 75

members is very convenient, other forms of locking members may be employed, such, for instance, as that shown at 40 in Fig. 4. Locking member 40 comprises a single strip of metal bent at its ends into cross or end bars 41 and intermediate its ends into a shank 42. It will be noted that shank 42 is bent in zig-zag fashion to afford an elastic connection between the cross bars 41. Thus shank 42 functions similarly to the shanks 18 and 18a of the members 17 and 17a.

While the invention has been described in connection with the joining together of structural members in miniature, it is to be understood that it may be applied for the purpose of securing together full sized structural members, for instance, parts of stage scenery, etc.

Although the members 11 and 28 have been illustrated as being solid, they may be provided with simulations of windows, doors, etc. either structurally or by painting.

Many structural parts may be secured in place by pressing one end bar 19 and a portion of the shank 18 into the grooves of a single member 11 at an intersection of said grooves in the regular way and leaving the remaining portion of the shank 18 and the remaining cross bar 19 free. Attachment of any part to the member 11 may be effected for instance by forming a hole or slot in said part just sufficiently large to pass the free cross bar 19 therethrough. Said cross bar 19 may then be made to engage the face of said part on opposite sides of said hole to hold said part in place.

Many other uses will suggest themselves to persons skilled in the art upon becoming familiar with this invention.

Although a specific embodiment of the invention has been illustrated and described in detail there are many changes and variations which may be made without departing from the invention and I desire to include all such changes and variations within the scope of the appended claims.

I claim:

45. 1. In combination; a pair of structural members arranged with one face of one member in abutting relation with a face of the other to form an angularly disposed portion of a building structure, each of said members being provided on other, adjacent faces thereof with a longitudinal groove and a transverse groove intersecting the latter, portions of the grooves in the abutted members being in alignment; and a resilient connector having a zig-zag shaped metal shank engaged in the aligned groove portions and a pair of metal cross-bars respectively engaged in a transverse groove of one member and a longitudinal groove portion in the other member for interlocking said members.
50. 2. In combination, a plurality of structural members arranged in abutting relationship to form a portion of a building structure, each of said members having a longitudinal groove and a plurality of spaced cross grooves in at least one end of said member and forming substantially cruciform shaped depressions therein, the abutting members being so positioned that the adjacent cross and longitudinal grooves of each pair of abutting members cooperate to form at their junction cruciform recesses for receiving similarly shaped connecting members therein, and a plurality of resilient substantially I-shaped connecting members, the cross pieces of which are of suitable dimensions to fit in said cross and longitudinal grooves and the shanks of which are suffi-

ciently short to necessitate longitudinal stretching of said connecting members in order to locate the cross bars of said members in the receiving grooves of said cruciform recesses formed by the abutting members, thereby creating, upon insertion of said connectors in said recesses, a tension which causes the abutting surfaces of the connected members to be in close frictional contact such that the joined members resist separation by transverse and vertical movements of the members in opposite directions.

3. In combination, a structural member provided on one face with a longitudinal groove and an intersecting transverse groove forming a substantially cruciform shaped locking depression 15 adjacent the end of said face, and a resilient I-shaped connector consisting of a shank and a substantially rectangular shaped cross bar at each end of said shank, said connector being partially engaged in said depression and partially projecting 20 beyond said member for interlocking the latter with an abutting structural member, the shank of said connector being sufficiently short to necessitate longitudinal stretching thereof to connect the member in which it is partially recessed with the abutting structural member, whereby close contact between the two members will be provided.

4. In combination, a structural member rectangular in cross section and provided at one 30 end with a longitudinal groove centrally disposed between opposite side edges of said end and intersected at right angles by a transverse groove which extends through the side edges of said end to form therein a substantially rectangular 35 cruciform shaped locking depression, and a resilient I-shaped connector consisting of a solid soft rubber shank and a solid soft rubber substantially rectangular shaped cross bar at each end 40 of said shank, one of said cross bars being engageable in either groove of said cruciform depression, said shank being partially engageable in the other groove and partially projecting beyond said member for acting with its other projecting cross bar to connect said member to an 45 abutting similarly grooved structural member at any side of the former, the shank of said connector being normally slightly shorter than the distance between the cross bar engaging grooves 50 in the respective abutting members so that once the connector is located in the cruciform locking depression of said members it will exert a tensioning force and thereby hold the abutting members in intimate frictional contact.

5. In combination, a structural member provided on one face with a longitudinal groove disposed centrally between opposite edges of said face and a plurality of equally spaced transverse grooves intersecting said longitudinal groove at right angles to form a plurality of contiguous 60 rectangular shaped cruciform locking depressions therein, and a plurality of resilient I-shaped connectors each having a substantially rectangular shaped cross bar engageable in the longitudinal portion of any depression and extending at right angles to a shank which has another substantially rectangular shaped cross bar on its other end, said shank being partially engageable 65 in the transverse portion of said depression and partially projecting from said member for connecting with its other cross bar another similarly grooved structural member thereto at either side thereof in any of a number of positions corresponding to the number of depressions, the shank 70

75

of each of said connectors being of such length that it must be stretched longitudinally to enable its projecting cross bar to engage the intended receiving groove in the abutting member, and once it is fully engaged to hold said members in frictional contact with each other.

6. In combination, a plurality of structural members arranged in abutting relationship to form a portion of a building structure, each of 10 said structural members having intersecting longitudinal and transverse grooves, a plurality of frictional contact connecting members, each of substantially I-shaped construction and made of elastic material, the intersecting grooves of said 15 abutting members forming rectangular I-shaped depressions suitable for receiving said I-shaped connecting members, said connecting members being of such dimensions that each of the cross bars thereof is adapted to engage at least one 20 of the walls of adjacent transverse grooves when inserted therein and to resiliently hold the abutting members in close physical contact with each other.

7. In combination, a pair of structural members arranged with one face of one member in abutting relation with a face of the other to form an angularly disposed portion of a building structure, each of said members being provided on other adjacent faces thereof with a longitudinal groove and a transverse groove intersecting the latter, portions of the grooves in the abutted members being in alignment, and a substantially I-shaped rubber connector having an elastic shank engaged in the aligned groove portions 35 and a pair of elastic cross-bars respectively engaged in a transverse groove of one member and a longitudinal groove portion of the other member for interlocking said members in close fric-

tional contact such that the members will not become disconnected by the vertical and horizontal stresses normally encountered in handling and using the building structure.

8. In combination, a pair of structural members adapted to be arranged edge to edge in abutting relationship to form a flat surface, a beam shaped structural member having opposite portions adjacent one surface adapted to be received between said structural members at said abutting edges, cross grooves in one face of each of said structural members, the cross grooves adjacent said abutting edges of said structural members adapted to cooperate to form I-shaped depressions, and I-shaped rubber locking members adapted to be stretched and pressed into said depressions, said locking members being of such dimensions that when they are stretched and placed in the depressions they tend to spring back and force said structural members into close contact with each other.

9. In combination, a structural member provided on one face with a longitudinal groove and an intersecting transverse groove forming a connecting means receiving depression in said face, and a resilient connector having a shank and end pieces partially engaged in said depression and partially projecting beyond said member for connecting the latter with another structural member, the dimensions of said connector being such that it must be stretched before insertion in said other member and when inserted tends to contract thereby holding the connected members in intimate contact sufficient to prevent the members becoming disconnected during their normal intended use.

HANS P. LUHN.
